Patented Oct. 8, 1963

196,526

DINNER PLATE OR SIMILAR ARTICLE

Michael J. Szymanski, Howlett Hill Road, R.D. 1, Camillus, N.Y.

Filed Oct. 3, 1962, Ser. No. 71,985

Term of patent 14 years

(Cl. D44—15)

The FIGURE is a plan view of a dinner plate of conventional configuration, showing my new design, a repeat unit of which is enclosed within the dot-dash line, and which repeats about the circumference in the manner shown.

I claim:

The ornamental design for a dinner plate or similar article, as shown and described.
